UNITED STATES PATENT OFFICE.

HENRY D'OLIER, JR., OF PHILADELPHIA, PENNSYLVANIA, ASSIGNOR, BY MESNE ASSIGNMENTS, TO GENERAL ELECTRIC COMPANY, A CORPORATION OF NEW YORK.

DESIGN FOR A REFLECTOR AND ATTACHMENT.

42,961.

Specification for Design.

Patented Sept. 3, 1912.

Application filed May 25, 1910. Serial No. 563,443. Term of patent 14 years.

To all whom it may concern.

Be it known that I, HENRY D'OLIER, Jr., a citizen of the United States, residing at Philadelphia, county of Philadelphia, and State of Pennsylvania, have invented a new, original, and ornamental Design for a Reflector and Attachment, of which the following is a specification.

Reference is to be had to the accompanying drawings, in which:

Figure 1 is a side elevational view of my reflector and attachment. Fig. 2 is a top plan view of the same.

The distinguishing characteristics of my design are the reflector member R of bowl shape surmounted by an ornamental extension 1 which, in turn, is surmounted by the part 2 of smaller diameter.

I claim:

The ornamental design for reflector and attachment, as shown and described.

HENRY D'OLIER, JR.
